T. H. Triplett,
Inventor

By Clarance A. O'Brien,
Attorney

UNITED STATES PATENT OFFICE.

THOMAS H. TRIPLETT, OF PATTERSON, NORTH CAROLINA.

JAR HOLDER.

Application filed July 2, 1924. Serial No. 723,756.

To all whom it may concern:

Be it known that I, THOMAS HARLEY TRIPLETT, a citizen of the United States, residing at Patterson, in the county of Caldwell and State of North Carolina, have invented certain new and useful Improvements in Jar Holders, of which the following is a specification.

This invention relates to jar holders, and 10 has particular reference to a device that is to be employed in the holding of jars for facilitating the filling and closing of the same.

The primary object of my invention resides in the provision of a jar holder of the above character, that is so constructed as to encompass practically the entire ring of the jar for thereby preventing the wobbling or slipping of the jar from within 20 the holder during the filling or closing operation.

A further and important object of the invention is to provide an article of this character which is relatively simple of construction, inexpensive of manufacture and well adapted for the purposes designated.

With the foregoing and other objects in view as the nature of the invention will be better understood, the same comprises 30 the novel form, combination and arrangement, providing a jar holder hereinafter more fully described, shown in the accompanying drawing and claimed.

In the drawing wherein like reference 35 characters indicate corresponding parts throughout both of the views:

Figure 1 is a side elevational view of a jar holder constructed in accordance with the present invention, and

Fig. 2 is a top plan view thereof.

Now having particular reference to the drawing, my novel jar holder constitutes the provision of a plurality of spaced metallic bands, preferably three in number, and 45 designated by the reference characters 5, 6 and 7, respectively. These metallic bands are arranged vertically with respect to each other, and are secured in such relation through the medium of a sheet metal strip 8, secured to the bands through the medium of rivets 5', 6' and 7', respectively. As

clearly shown in both of the figures of the drawing, this strip 8 is attached to the bands at the rear side thereof. Similar ends of the upper and lower bands 5 and 6 extend inwardly along side of the opposite ends thereof, as clearly shown in Fig. 2, for closing the space that would otherwise exist between the ends of these bands and for permitting of the entire circling of the 55 jar. The intermediate band 6 has one of its ends extended inside of the opposite end thereof, and said extended end of this band is directly opposite the extended ends of the upper and lowermost bands, which will 60 result, when the bands are contracted, in the more efficient clasping of the jar. 65

Secured to the outermost ends of the upper and lower bands 5 and 7 and to the innermost bands 6 at a point spaced from the inwardly extending end thereof is a vertically arranged metal strip 9, while similarly secured to the outermost end of the central band 6 and at points spaced from the inwardly extending ends of the upper 70 and lower bands 5 and 7 and in line with the outer end of said band 6 is a similar metallic strip 10. Each of these strips is formed with an outwardly laterally extending handle 9' and 10' respectively, it 75 being noted from Fig. 2 that these features are substantially parallel and are in spaced relation with respect to each other. 80

The tendency of the metallic bands is to spring to an open position or in other words, 85 the springy nature of these bands result in such an opening of the bands as to permit of the ready positioning of the article over a jar. It is of course apparent that after this holder is disposed over a jar, the forcing of the handles 9' and 10' together will 90 result in the closing of the bands upon the jar and the effective holding of the same.

The advantages of a jar holder of this character will be readily appreciated, and 95 even though I have herein shown and described the most preferred embodiment of the invention with which I am at this time familiar, it is nevertheless to be understood that minor changes may be made in the invention, without departing from the spirit 100 and scope of the appended claim.

Having thus described my invention, what I claim as new, and desire to secure by Letters-Patent, is:

5 A jar holder comprising a pair of strips each having a handle located at a point intermediate its ends, a pair of bands disposed transversely of the strips, one end of one band being attached to one strip and an intermediate portion to the other strip, one

end of the other band being attached to the 10 other strip and an intermediate portion to the first strip, the portions of the bands extending from the attached intermediate portions overlapping the strips to which their ends are attached.

15 In testimony whereof I affix my signature.

THOMAS H. TRIPPLETT.
